UNITED STATES PATENT OFFICE.

RALPH L. SKINNER AND EDMOND H. LAMBERT, OF DETROIT, MICHIGAN, ASSIGNEES
TO SKINNER AUTOMOTIVE DEVICE CO., INC., OF DETROIT, MICHIGAN, A CORPORA-
TION OF CALIFORNIA.

SLEEVE TYPE OF INTERNAL-COMBUSTION-ENGINE LUBRICATION.

Application filed September 13, 1926. Serial No. 135,046.

This invention relates more particularly to the lubrication of the sleeve or sleeves of the Knight or other sleeve styles of engines, especially the upper portions of such moveable sleeves, and in such a way as to assure adequate oil application, but without undue consumption of oil.

In one form of the invention, oil or oily vapor is fed into the sealing-head compartments of the engine and the admitted oil, or a part of it, flows down the sleeves, preferably in channels provided in their surfaces for that purpose, and the excess oil is withdrawn through ports below and adjacent to the inlet ports of the engine.

In the preferred embodiments of the invention illustrated in the accompanying drawings, forming a part of this specification, and throughout the several views of which like reference numerals have been employed to designate the same parts, the construction is such that a continuous suction is applied to the sleeve grooves or channels referred to, and an intermittent suction, through a properly-metered port or hole, is applied to an oil-collecting channel of the piston, whereby its contents are withdrawn interruptedly, the abstracted oil from both sources passing through a rectifier, in which it is purified, the reclaimed oil being delivered back to the oil-supply of the engine, while the air, gases and vapors go into the engine, through the intake-manifold, where they are consumed with the gaseous fuel.

In these drawings—

Fig. 1 is a vertical section through one cylinder of a sleeve-principle, internal-combustion engine, showing one cylinder only thereof and the associated oil-rectifier;

Fig. 2 is an enlarged, fragmentary, vertical section illustrating portions of the engine-cylinder, the sleeves and the piston;

Fig. 3 is a fragmentary elevation of the inner sleeve;

Fig. 4 is a similar view of the outer sleeve; and

Fig. 5 shows, partly in section and partly in elevation, a slightly-modified construction of a portion of the appliance.

Looking at the drawings, especially Figs. 1 to 4, inclusive, it will be observed that, in this instance, which shows only one cylinder of a multi-cylinder engine, the structure

includes such cylinder 11, the outer, reciprocating sleeve 12, the companion, inner, sliding sleeve 13, the piston 14, the associated connecting-rod 15, the usual intake-manifold 16, the corresponding admission or inlet port 17, the correlated exhaust-port 18, the connected exhaust-manifold 19, and the oil rectifier 21 of known construction, the cylinder, sleeves and piston being supplied with lubricant, as by the splash or other known system.

As is clearly illustrated, the upper section only of the rectifier projects into a downward extension 22 of the exhaust-manifold, which is equipped with a control valve 23, whereby such portion of the oil purifier, in which the separation or volatilization of gasifiable, contaminating constituents occurs, is heated more or less, depending upon the adjustment or position of the movable valve.

As is customary, the reclaimed, purified oil is delivered intermittently through a discharge pipe 20 into the engine crank-case 24, where it mixes with the main oil-supply therein and is ready for re-use.

The interior of the rectifier is connected by a pipe 25 to the intake-manifold of the engine, so that the suction in the latter is exerted through the rectifier in the usual way.

Such rectifier or purifier is also connected by a pipe 25 to a flattened, tubular member or manifold, arranged along the sides of all of the engine-cylinders and joined to their ports 27, through the walls of the cylinders, directly below their intake or inlet ports 17, by hollow, securing screws 28.

Referring to Fig. 2, it will be seen that each piston 14 has an external, transverse, circumferential oil or fluid collecting groove 29 around it, desirably, but not necessarily, located between two of the several piston-rings 31, 31 with which the piston is equipped, an air-relief port or bleeder-hole 32 extending inwardly through the wall of the piston and connecting at its outer end with the groove or channel 29, and at its inner end with the space inside the piston, so that such channel 29, through this small port, is in communication with the upper part of the interior of the engine crank case.

The inner sleeve 13 has the usual ports for the admission of the explosive mixture to

and the discharge of the exploded gases from the cylinder.

It also has a plurality of external, transverse channels 33, 34 and 35, the extreme, 5 upper one 33 extending completely around the sleeve, the intermediate ones 34 likewise completely surrounding the sleeve, the lower ones 35 being of less length and not continuing throughout the entire circumference.

10 An external, longitudinal channel 36 on such inner sleeve, in register with the port 27 and positioned between the ends of the channels 35, connects at its upper end with the two, transverse grooves 34, 33, and at its 15 lower end is in communication with a small, metered hole 37 through the sleeve and having a flaring mouth 38 on the inner side of the sleeve, and with which the piston channel 29 is designed and arranged to come into 20 register or communication, interruptedly or intermittently, as shown, for example, in Fig. 2.

Similarly, the outer sleeve 12, likewise having inlet and exhaust ports, has outside, 25 transverse channels 39 extended all the way around the sleeve, and other, lower channels, which may be of the same length or shorter.

This outer sleeve 12 also has an external, lengthwise, surface channel 42 in alignment 30 with the cylinder port 27, its upper part connecting with the channels 39, its lower section being connected to the longitudinal channel or groove 36 of the inner sleeve by a hole or port 43 of substantial size through 35 the sleeve.

The top surface of the inner sleeve is connected to its uppermost groove 34 by inclined or oblique surface-channels 44 on opposite sides thereof, and, analogously, the 40 top surface of the outer sleeve is joined to its corresponding groove 39 by similar, sloping surface-channels 45.

Obviously, from an understanding of this construction, it will be seen that the suction 45 present at the cylinder port 27 is exerted intermittently or discontinuously on the reciprocating, fluid-collecting channel 29 of the piston, and continuously on the lower sleeve grooves 34 and 39 and on the sealing-head 50 compartment through the specified surface-grooves 34, 44 and 39, 45 of the sleeves, the channels 36 and 42 being always in communication with the cylinder-port.

Each sealing-head compartment of the engine has an admission port 46 through its side-wall, and in order that such opening 55 may not be closed during the reciprocation of the corresponding, outer sleeve, the latter is cut away or recessed at 47 (Figures 1 and 3).

All of such ports 46 of the several engine cylinders are connected to a common, tubular manifold 48, which, in turn, is joined by a pipe 49 to the delivery pipe 20 of the 60 rectifier, such pipe 49, at its junction with

the oil-discharge pipe 20, having within it a plug with a suitably-metered, small hole 51.

The operation of the appliance occurs practically as follows, the suction present at each cylinder-port 27, by reason of the partial vacuum in the intake-manifold working through the piping and rectifier (a) interruptedly withdraws aerated, impure or contaminated oil from the fluid collecting groove 29 of the piston through the passages 38, 37, 36 and 43, and delivers it into the rectifier through the pipe 26; (b) continuously removes and discharges into the rectifier through pipe 26 the accumulated polluted oil from the lower groove 39 of the outer sleeve 12 and from the lower groove 34 of the inner sleeve 13 through the lengthwise channels 36 and 42 and port 43; and (c) whenever the rectifier delivers its charge of stored, reclaimed oil through the pipe 20 to the engine crank-case, draws a portion of said oil up through the pipe 49 into the sealing-head compartment, down through the inclined grooves 45 and 44 of both sleeves, through the upper circumferential sleeve grooves 39 and 34 and out through the channels 42 and 36 and the sleeve and cylinder ports 43 and 27 into the rectifier, the oil from these three sources after purification being returned through pipe 20 to the crank-case, except for the small amount thus intercepted and carried to the sealing-head compartment.

Such abstraction of oil from the piston effects the well-known, advantageous results 100 regarding the improved functioning of the engine, and the passage of the oil through the sealing-head compartment assures an adequate, but not excessive, lubrication of the upper sections of the moving sleeves, 105 from which some oil, which would usually reach them, is directly withdrawn before it arrives there, by the suction existent at the cylinder-port 27, below its corresponding intake-port.

Thus the passage of oil through the sealing-head chamber compensates for the withdrawal of oil below the intake port, such extraction of oil at the point indicated removing a certain amount which would otherwise 115 travel all the way up the sleeves, and possibly keep them adequately lubricated, or be lost through the intake-port.

As will be readily understood, the piston air-inlet or bleeder-port 32 permits the inflow of a small amount of air which relieves the vacuum in the piston groove 29, thus facilitating the withdrawal of its contents and aerating the abstracted fluids or liquids in a manner well understood.

Part of the time, the passage 38, 37 through the inner sleeve is in communication with the fluid-collecting groove 29 of the piston, and, for a portion of the time, such passage is uncovered due to the rise of the 120

piston beyond it, but the shape and caliber of the passage is such that the air then flowing through it is so small as not to disturb the proper gaseous fuel mixture in the intake-manifold.

In view of the fact that the passage through the pipe 49 has the small, regulating or metered orifice 51, the amount of air entering the intake-manifold through this lubrication system is insufficient to interfere with correct carburation.

The source of oil-supply for the sealing-head compartments is largely immaterial, and such oil may be drawn from any part 15 of the engine lubrication-system which is qualified to afford such a supply.

In Fig. 5, a slightly-modified structure is shown, wherein the oil-supply pipe 52 for the sealing-head compartment is connected 20 directly to the interior of the top portion of the crank-case chamber 24, through a plug 53 having a small, metered hole therethrough, which prevents an excess of air being drawn through the sealing-head compartment into the intake-manifold.

Otherwise, this modified structure functions in much the same way as the other one, the suction drawing the oily vapor in the upper part of the crank-case into and 30 through the compartment specified, wherein it performs its lubricating function.

Still other embodiments of the invention are possible, but it is unnecessary here to present them, since it may be borne in mind 35 that many minor changes may be made in the structures set forth without departure from the essence of the invention, and without the loss of any of its material benefits.

We claim:

40 1. In an internal-combustion engine, the combination of an engine-cylinder having intake and exhaust ports, sleeve means in said cylinder controlling said ports, means to move said sleeve means, a reciprocatory piston in said sleeve means, means to lubricate said cylinder, sleeve means and piston, and additional means to introduce lubricant into the sealing-head compartment of the engine and to remove at least a part of such lubricant after it has passed down a portion of the length of said sleeve-means.

45 2. In an internal-combustion engine, the combination of an engine-cylinder having intake and exhaust ports, sleeve means in said cylinder controlling said ports, means to move said sleeve means, a reciprocatory piston in said sleeve means, means to lubricate said cylinder, sleeve means and piston, and additional means to introduce lubricant into the sealing-head compartment of the engine and to remove at least a portion of such lubricant from the engine-cylinder below said sealing-head compartment.

50 3. In an internal-combustion engine, the combination of an engine-cylinder having

intake and exhaust ports, sleeve means in said cylinder controlling said ports, means to move said sleeve means, a reciprocatory piston in said sleeve means, means to lubricate said cylinder, sleeve means and piston, and additional means to introduce lubricant into the sealing-head compartment of the engine and to remove at least a portion of such lubricant from said sleeve means and from the engine-cylinder at a point below one of 75 said ports of the latter.

4. In an internal-combustion engine, the combination of an engine-cylinder having intake and exhaust ports, sleeve means in said cylinder controlling said ports, means to move said sleeve means, a reciprocatory piston in said sleeve means, means to lubricate said cylinder, sleeve means and piston, and additional means to introduce lubricant into the sealing-head compartment of the engine 80 and to remove at least a portion of such lubricant from said sleeve means and from the engine-cylinder at a point below said intake-port.

5. In an internal-combustion engine, the combination of an engine-cylinder having intake and exhaust ports, a reciprocatory piston in said cylinder, inner and outer channeled sleeves in said cylinder between said piston and cylinder, said outer sleeve having an oil port therethrough, means to lubricate said cylinder, piston and sleeves, means to move said sleeves, and means to introduce lubricant into the sealing-head compartment of the engine and to remove at least a portion of such lubricant through 95 said sleeve-port after it has flowed down between and for a portion of the length of said sleeves.

6. In an internal-combustion engine, the combination of an engine-cylinder having intake and exhaust ports, a reciprocatory piston in said cylinder, inner and outer channeled sleeves in said cylinder between said piston and cylinder, said outer sleeve having an oil port therethrough, means to lubricate said cylinder, piston and sleeves, means to move said sleeves, and additional means to introduce lubricant into the sealing-head compartment of the engine and to remove at least a portion of such lubricant through 100 the engine-cylinder wall from both of said sleeves after it has flowed down their channels for a part of the length of the sleeves.

7. In an internal-combustion engine, the combination of an engine-cylinder having intake and exhaust ports, sleeve means in said cylinder controlling said ports, means to move said sleeve means, a reciprocatory piston in said sleeve means, means to lubricate said cylinder, sleeve means and piston, a lubricant-conduit connected to the sealing-head compartment of the engine and open 115 to the atmosphere at least part of the time, said sleeve means having passage means 120

- connecting said sealing-head compartment with an oil-port through the cylinder-wall below the cylinder intake-port, and means connecting said cylinder oil-port with the intake-manifold of the engine, whereby the suction in such manifold draws lubricant into and from said compartment through said conduit, passage-means, and cylinder oil-port, the smallest caliber of said lubricant-conduit limiting the amount of admitted air to prevent interference with the engine carburation.
8. In an internal-combustion engine, the combination of a ported engine-cylinder, a reciprocatory piston in said cylinder, sleeve means between said piston and cylinder controlling the ports of the latter, means to move said sleeve means, a crank-case adapted to contain lubricant, means to draw oily vapor from said crank-case into the sealing-head compartment of the engine and means to cause the contents of said sealing-head compartment to flow down a portion of the length of said sleeve means.
9. In an internal-combustion engine, the combination of a ported engine-cylinder, a reciprocatory piston in said cylinder, sleeve means in said cylinder controlling the ports of the latter, means to move said sleeve means, a crank-case adapted to contain lubricant, a conduit having a constriction connected to the upper portion of said crank-case and to the sealing-head compartment of the engine, said cylinder having an oil-port through its side-wall below said compartment, said sleeve means having surface channel means connecting said compartment with said cylinder oil-port, and means to apply the suction of the engine intake-manifold to said oil-port to draw oily vapor of the crank-case into and from said compartment.
10. In an internal-combustion engine, the combination of a ported engine-cylinder, a reciprocatory piston in said cylinder, sleeve means in said cylinder controlling the ports of the latter, means to move said sleeve means, a crank-case adapted to contain lubricant, a conduit connected to said crank-case and to the sealing-head compartment of the engine, said cylinder having an oil-port through its side-wall below said compartment, said sleeve means having surface channel means connecting said compartment with said cylinder oil-port, and means to
- apply the suction of the engine intake-manifold to said oil-port to draw oily vapor of the crank-case into and from said compartment.
11. In an internal-combustion engine, the combination of a ported engine-cylinder, a reciprocatory piston in said cylinder having a lubricant-collecting channel, sleeve means controlling the ports of said cylinder between the latter and said piston, means to move said sleeve means, means to lubricate said cylinder, piston and sleeve means, means to substantially continuously remove lubricant from the sealing-head compartment of the engine, and means to intermittently remove lubricant from said piston channel.
12. In an internal-combustion engine, the combination of a ported engine-cylinder, a reciprocatory piston in said cylinder having a lubricant-collecting channel, sleeve means controlling the ports of said cylinder between the latter and said piston, means to move said sleeve means, means to lubricate said cylinder, piston and sleeve means, means to substantially continuously remove lubricant from the sealing-head compartment of the engine through a port through the side-wall of the engine-cylinder, and means to intermittently remove lubricant from said piston channel through the same port.
13. In an internal-combustion engine, the combination of a ported engine-cylinder, a reciprocatory piston in said cylinder having a lubricant-collecting channel, sleeve means between said piston and cylinder controlling the ports of the latter, means to move said sleeve means, means to lubricate said cylinder, piston and sleeve means, said cylinder having an oil-port, said sleeve means having a conduit with a constriction connected to said oil-port and with which said piston-channel intermittently registers, a lubricant-conduit having a constriction connected to the sealing-head compartment of the engine and open to the atmosphere at least part of the time, said sleeve means having passage means connecting said compartment with said oil-port, and means connecting said oil-port with the intake-manifold of the engine.

In witness whereof we have hereunto set our hands.

RALPH L. SKINNER.
EDMOND H. LAMBERT.
